SOLOMON E. AARON, OF BOSTON, MASSACHUSETTS.

CAR-TRUCK SUPPORT.

1,205,071.

Specification of Letters Patent.

Patented Nov. 14, 1916.

Application filed March 11, 1916. Serial No. 83,627.

To all whom it may concern:

Be it known that I, SOLOMON E. AARON, a citizen of the United States, residing at Boston, in the county of Suffolk and State of Massachusetts, have invented certain new and useful Improvements in Car-Truck Supports; and I do hereby declare the following to be a full, clear, and exact description of the invention, such as will enable others skilled in the art to which it appertains to make and use the same.

This invention relates to railway rolling stock, and more especially to four-wheel trucks; and the object of the same is to produce a support by means of which the truck frame can be connected with the car body, whatever the relative position of these two elements.

It often occurs in times of accident that an injured person lies across or between the rails and under, between, or very near the wheels of one truck, which wheels may have been derailed or may not. It is found to be impossible to remove the injured person without raising the trucks, and yet when a jack or jacks are used for raising the car body, the head or cotter pin at the lower end of the king-bolt may be sheared off, when the truck would drop back on the injured person. This is rendered more likely by the additional weight which one or more motors on one or both axles will produce. Heretofore resort has been made to a special form of jack by means of which the truck could be raised, and in its elevation it would lift the car body; but these jacks are not always present, or if present the position of the car and the condition of its surroundings are not such as permit the use of this type of jack, and especially its quick use so as to save the life of an injured person.

For instance, on open cars having running boards along their sides it is often necessary to saw or smash a running board in order to permit the use of a jack and its crow-foot so that the latter may engage the truck or truss rod between the wheels thereof. In a subway or in other places where space is limited as, for instance, along a platform, if a car becomes derailed with a person beneath or near the truck it is not always possible to insert a jack from the side and therefore it is sometimes used under the end of the car or beneath the end of one of its sills.

The purpose of the present invention is to provide a support by means of which

some available and accessible part of the truck frame can be quickly connected with some available and accessible part of the car body at several points, after which the support is adjusted so as to make the connection tight, and then when the body is lifted by the jack or other means, the truck is lifted with it. This object is carried out by the use of a support hereinafter more fully described and claimed, and as shown in the drawings wherein:

Figure 1 is a bottom plan view of one end of a car, showing its truck turned at an angle to its body and illustrating a pair of the rods described herein. Fig. 2 is a cross section through the floor of the car body and its sills, on about the line 2-2 of Fig. 1, showing one of said cross rods and the supports therefor. Fig. 3 is an enlarged sectional detail of the coupling hereinafter referred to. Figs. 4 and 5 are sectional details of two different types of supports for this coupling, that in Fig. 5 being illustrated in dotted lines in Fig. 3. Fig. 6 is a detail showing one of said couplings hung at one end on a cross rod, and supported in idle position by a latch beneath the car.

In the drawings I have employed the letter F to designate the car floor and S its sills, that shown in Fig. 4 being of wood and that shown at S' in Fig. 5 being a steel I-beam, although I do not wish to be limited in this particular. The letter T designates broadly the frame of the truck having wheels W and axles A, and one or both of the latter may have motors M as shown; and this entire truck is mounted on a king-bolt designated by the letter K. No novelty is claimed for the parts thus far described and they are only diagrammatically shown in the drawings.

Coming now to the gist of the present invention, and referring first to Fig. 3, the coupling forming the portable part of my improved truck support comprises an upper member 1 having its upper end hooked at 2 and its lower end threaded to the right at 3; a lower member 4 having its lower end hooked as at 5, and its upper end threaded to the left as at 6; and a turn-buckle 7 between these members, oppositely threaded at the opposite ends of its bore as usual, and provided at its mid-length with any suitable form of handle 8 such as a wheel or a series of pins. It is obvious that when the upper hook 2 is engaged with a suitable support

and the lower hook 5 with some element which it is desired to raise, and the turn-buckle is rotated in the proper direction, the coupling will be reduced in length and the 5 element will be raised. It follows that if the upper hook is engaged with some part of the car body and the lower hook with some part of the truck, this coupling may be used to lift that part of the truck. I provide each 10 car with a number of these couplings which are not of excessive weight or size and may be easily carried at a proper point, and as explained below I provide each car adjacent each of its trucks with suitable members 15 which may be quickly found and readily used as supports for the upper hook of the coupling, while the lower hook thereof will be engaged with any part of the truck which can also be conveniently reached. 20 The numeral 10 designates a rod extending across beneath the car body, and by preference one of these rods is located nearly above the normal position of each axle. The body of the rod preferably has depressions 25 at intervals as indicated at 11 in Fig. 2. Its ends may be turned upward and connected directly with the sills S or S', or said ends may be fastened to the sills by any suitable means as indicated in the same view 30 at 12. Additional means may be employed between the ends of the rod for connecting it with and supporting it from the floor F, as indicated in the same view at 13. In addition to these supports, I may also provide others, such as the truss 23 and link 24 35 shown in Fig. 2. The long rods 11, firmly held beneath the car body by any or all of these means, thus constitute supports for couplings which may be adjusted transversely of the car as the position of a derailed truck may demand. But as it often occurs that a coupling is needed directly beneath the sill, I provide other supports such as eye-bolts or screw eyes 14 engaging sills 40 S of wood as seen in Fig. 4, or clamps engaging an I-beam as seen in Fig. 5. In this view each clamp is shown as made of two members 15 and 16 with hooked upper ends engaging the lower flange of the beam S', 45 and two bolts 17 and 18 through the depending straight arms of these members and over either of which the upper hook 2 of the coupling could be passed. It is obvious that the clamps could be slid along on the I-beam 50 sills S', and by this means the coupling could be adjusted longitudinally beneath the car. Yet other supports for the coupling might also be mounted in these sills or other portion of the car body, and need not be 55 illustrated. With several of these fixed supports beneath each sill as indicated in Fig. 1, and with cross rods as also therein shown, there would be some points with which the upper hooks of three or four couplings could 60 be engaged—no matter how far the truck 65

had been turned from its normal position by the supposed accident. It is even possible to have several of the couplings permanently though loosely connected with some of the supports, and held out of the way in idle 70 position as seen in Fig. 6. Herein the upper hook of a coupling is shown as engaged with a rod 10 and is carried clear around the same in the form of an eye 2', rather than a hook which might be jolted off; and 75 when this coupling is not in use it is swung up under the car floor and supported in idle position by any appropriate form of latch 20, such as a piece of strap or a link.

In the use of this truck support, let us 80 assume that an accident has occurred and, either because an injured person lies on the track adjacent a truck, or because the wheels are derailed and the entire truck must be raised with the car body, it is desirable to 85 quickly connect the truck frame with said body so that when the latter is jacked up the former will move with it. Such couplings as are permanently connected with their supports as seen in Fig. 6 and are in 90 position where they can be used, are unlatched and let down, and others have their upper hooks 2 engaged either with the rods 10 or with some of the supports in the sills. The lower hooks of the couplings so used 95 are engaged with some part of the truck T, and then the handles 8 are manipulated so that the turn-buckles 7 are turned in the proper direction to tighten all the couplings. Thus the truck is quite firmly connected 100 with the car body at several points, preferably not less than three points around the king-bolt. When now said body is raised by means of a jack or otherwise, it is obvious that the entire truck rises with it. If 105 the upper end of each coupling engaged a fixed support such as shown in Figs. 4 and 5 for instance, or if it engaged one of the depressions 11 in a rod 10, it cannot move out of place in case the truck swings or tilts 110 on its king-bolt as its weight comes off the ground. It is even possible to use a plurality of these couplings at either side of the break in an axle, so that such axle will not cant in its boxes or fall out of the same. 115 Thus I have produced a truck support which is ever ready for instant application in case of need, and which as a whole includes some or all of the supporting elements on the car, and a series of the elements hereinbefore 120 described as couplings.

What I claim is:

1. In a car truck support, the combination with a coupling consisting of two hooked members and adjustable means connecting their shanks for drawing them toward each other; of a series of supports carried by and beneath the car body, some extending transversely and others longitudinally thereof and all located in proximity 125 130

to its truck, whereby the hook of the upper member of a coupling may be adjustably engaged with a support and that of the lower member with the truck frame, for the purpose set forth.

2. In a car truck support, the combination with a coupling consisting of two hooked members and adjustable means connecting their shanks for drawing them toward each other; of rods extending across beneath the car body above and in proximity to each truck and having depressions at certain points along their length, means for supporting said rods from the car-sills, and other means for supporting them at other points.

3. In a car truck support, the combination with an I-beam forming the sill; of a clamp in two members having hooked upper ends embracing the lower flanges of said beam and bolts connecting their lower ends, and a coupling consisting of two hooked members and adjustable means for connecting their shanks, one hook adapted for engagement with said bolt and the other with the car truck.

In testimony whereof I affix my signature in presence of two witnesses.

SOLOMON E. AARON.
